UNITED STATES PATENT OFFICE.

JAMES M. BRESEE, OF MATTOON, ILLINOIS.

ROAD-MACHINE.

1,143,032.

Specification of Letters Patent.

Patented June 15, 1915.

Application filed October 25, 1913. Serial No. 797,333.

To all whom it may concern:

Be it known that I, JAMES M. BRESEE, a citizen of the United States, residing at Mattoon, in the county of Coles and State of Illinois, have invented certain new and useful Improvements in Road-Machines, of which the following is a specification.

This invention relates to improvements in drags and has for its object to provide a new form of drag adapted to crush and distribute dirt, loam or the like.

My device is especially adapted for use in connection with road grading machines where it is desired to distribute and smooth the dirt thrown into the center of the road, as well as to crush any clods or lumps contained in such dirt.

Another object is to provide means to form the crown of the road to the desired curvature.

Still another object of my invention is to provide a device of the class described which may be formed of separable sections, flexibly connected, so that additional sections may be added thereto or taken therefrom, if so desired.

Other objects will be set forth in the following specification and accompanying drawings, in which;

30 Figure 1 is a plan view of a drag embodying my invention; Fig. 2 is a side elevation of the same; Fig. 3 is a detail of a modified form of my device.

Like numerals refer to like elements throughout the drawings, in which 10 designates generally my drag having in the form shown in Fig. 1, for example, a plurality of members 11, 12, 13 comprising channel beams having the upwardly extending side flanges 11^a, 12^a, 13^a therein respectively. The webs 11^b, 12^b, 13^b of the respective members are provided with the apertures 11^c, 12^c, 13^c therein respectively, these apertures being provided with the enlarged portions 11^d, 12^d, 13^d and the comparatively narrow portions 11^e, 12^e, 13^e, respectively. Chains 14 are utilized to connect the members together and in assembling they may be passed through the enlarged portions of the apertures, as clearly shown in Fig. 1, and when the members are spaced apart and adjusted to suit the adjacent link of each chain, may be turned to permit its placement in the narrow portions 11^e, 12^e, 13^e with the respective

50 apertures, whereupon the succeeding link lo-

cated at right angles to such apertures will prevent the withdrawal of the chain when the drag is in operation. Additional fastening means may be used, if so desired. The chains are passed beneath the front of each member and inserted upwardly through the apertures and over the rear flange to the next succeeding member and so on. By this construction or arrangement, it will be apparent that as a pull is exerted upon the extremities of the chains 14, the action will be such as to slightly tilt or incline the respective members so that their rear edges are in contact with the surface over which they are passing. This operates to effectively distribute the accumulated dirt or where used to crush clods or the like will serve to fully and effectively break up and crush the same.

It will be apparent in Fig. 2 that I have constructed the member 11 comparatively light; the next succeeding member 12, I have shown as heavy in construction and the member 13 as still heavier. By this construction a gradually increasing crushing effort is applied to material acted on, as will be apparent.

Where used in forming roads in connection with road grading machines, I find it advantageous to employ members such as 15, shown in Fig. 3, the same being slightly curved to conform to the curvature of the crown of the road or to form the same with the desired curvature. In other respects this form resembles that previously described.

It will be obvious that I have provided an improved and practical form of road drag in which any desired number of crushing or distributing members may be utilized and which is economical and easy to manufacture and readily assembled or disassembled, as desired.

While I have shown and described my invention with more or less particularity, I do not wish to be restricted to such showing or description beyond the scope of the appended claims.

What I claim is:

1. In a device of the class described, a plurality of scraper members spaced apart, and a continuous link chain securing said members together, said members having apertures therethrough adapted to be detachably engaged by the desired links of said

- chain whereby said members may be spaced apart as desired. 35
2. In a device of the class described, a plurality of spaced apart scraper members, and flexible connecting members extending between and secured to said scraper members, said connecting members being arranged to pass over the following edges of said scraper members and beneath the leading edges of said scraper members and to tilt said members with respect to the surface being operated upon when said device is in operation. 40
10 3. In a device of the class described, a plurality of scraper members spaced apart, and flexible means securing said scraper members together to follow each other successively in the same path of travel, the scraper members toward the rear portion of said device being of greater weight per unit of length than the members toward the forward portion thereof. 45
15 4. In a device of the class described, a plurality of spaced apart channel beams having their channels upturned, flexible connections extending between and secured to said channel beams, said connections being arranged to tilt said beams when in operation. 50
20
25 5. In a device of the class described, a plurality of spaced apart members, chains extending between said members and secured thereto, said chains being passed through the underside of each member and over the back thereof to the next succeeding member. 55
30
35 6. In a device of the class described, a plurality of channel beams having their channels facing upwardly, chains extending therebetween and secured thereto, said chains passing through the web of said first channel beam from the underside thereof and being passed over the rear flange thereof to and under the succeeding channel beam. 60
35
40 7. In a device of the class described, a plurality of scraper members, said scraper members having apertures therethrough with slots leading therefrom, and flexible connecting members arranged to pass freely through said holes and to fixedly engage said slots whereby said members may be spaced apart, as desired. 65
45
50
55 8. In a device of the class described, a plurality of channel members, said channel members having apertures therethrough with slots leading therefrom, and chains arranged to pass freely through said holes and to fixedly engage said slots whereby said channel members may be spaced apart, as desired. 70
60
65
75

In testimony whereof, I have subscribed my name.

JAMES M. BRESEE.
